United States Patent Office

Des. 202,180
Patented Sept. 7, 1965

202,180

AUTOMOBILE

Virgil M. Exner, Sr., and Virgil M. Exner, Jr., Birmingham, Mich., assignors to Renwal Products, Inc., Mineola, N.Y., a corporation of New York

Filed Jan. 5, 1965, Ser. No. 83,283

Term of patent 14 years

(Cl. D14—3)

Fig.4

Fig.5

FIG. 1 is a front view of an automobile embodying our new design;

FIG. 2 is a rear view thereof;

FIG. 3 is a top plan view thereof;

FIG. 4 is a right side view thereof, the left side view (not shown) being a mirror image but otherwise identical thereto;

FIG. 5 is a front perspective view;

FIG. 6 is a rear perspective view thereof; and

FIG. 7 is a side perspective view thereof.

We claim:

The ornamental design for an automobile, as shown and described.
